ATTORNEY.

UNITED STATES PATENT OFFICE

MOTOGO JYUMI, OF OAKLAND, CALIFORNIA

LAMP

Application filed March 6, 1929. Serial No. 344,619.

The invention relates to an ornamental lamp, and particularly to the base thereof.

An object of the invention is to provide a lamp base wherein certain types of objects may be contained and displayed as decorative elements of the base in a protected and unchanging condition.

Another object of the invention is to provide a lamp base of the class described particularly adapted for the preservation and display therein of objects composed of organic materials.

A further object of the invention is to provide a particularly effective means for preserving the aforesaid objects while in the lamp base.

Yet another object of the invention is to provide a lamp base of the character described in which the contents thereof are arranged to be illuminated in a particularly direct and effective manner by the source of light mounted thereon.

The invention possesses other objects and features of advantage, some of which, with the foregoing, will be set forth in the following description of a preferred form of the invention which is illustrated in the accompanying drawings, in which,

Figure 1 is an elevation of a lamp structure embodying the invention, portions of the base and a shade of the lamp being broken away to disclose certain structural elements thereof.

Figure 2 is an enlarged fragmentary vertical and axial section of the central portion of the lamp structure.

As illustrated, the lamp of my invention comprises a base 3 of a vase-like outline and a light source 4 mounted on said base portion. The lamp is essentially decorative, and is here shown provided with a translucent shade 5 generally enclosing the light source, said light source, in the present instance, comprising an electric light globe. The base 3 is also arranged to provide deco-

rative elements for the lamp, and it is to the provision of a novel and attractive decorative base that the present invention particularly relates.

As particularly disclosed, the base portion 3 comprises a transparent vessel of glass or the like having a tubular neck portion 6 defining a mouth for the vessel cavity and a bottom portion 7 formed to support the lamp in upright position on any suitable supporting object or surface. The outline of the base 3 between the neck and bottom portions thereof is generally immaterial to the present invention; in the present instance, the base is seen to be generally cylindrical with a central bulge.

A closure member 8 is provided for the base, said member being preferably arranged to be so mounted on the base as to hermetically seal the cavity of the same. As shown, the closure 8 is provided with internal threads 9 for receiving threads 11 provided on the neck portion 6 of the base in integral relation thereto. For reasons to be herein-after brought out, at least the central portion of the cap 8 is desirably transparent, and the cap is, in the present instance, formed with a metallic rim portion 12 providing the threads 9 and arranged to engage around the outside edge of a disc-shaped top portion 13 formed of glass or the like for clamping the latter against the rim edge 14 of the neck. Preferably, and as shown, a gasket 15, or other suitable sealing medium, is interposed between the glass top 13 and the rim 14. In this manner, the cavity of the base is arranged to be hermetically sealed when the cap is mounted on the base. It is to be understood that other means than those particularly shown and disclosed might be utilized for disposing the cap to provide a sealed closure for the base.

The cap 8 is arranged to support the light globe 4, and, as shown, is carried in a socket 16 mounted on a support member 17 carried

on rods 18 fixedly engaged in and extending axially from the cap rim 12. The rods 18 are appropriately shaped to provide for the disposal of the globe 4 between them, it being noted that said globe is arranged to be disposed in inverted position whereby a considerable portion of the light therefrom is arranged to be directed downwardly and through the glass top of the cap. As shown, 10 the lead-in wires 19 to the socket 16 are disposed to extend upwardly along a rod 18, it being noted, however, that these rods might be tubular for receiving the wires 19 therethrough if a maximum concealment of these 15 wires is desired. The support member 17 is also seen to provide a mounting for the shade 5, by means of a spider-plate 20, said shade being of any appropriate design. In this manner, the cap rim is arranged to support 20 both the light globe 4 and shade 5 in their operative positions.

It will now be noted that the cavity of the base is arranged to receive decorative articles 21, which, on account of their visibility 25 through the base walls serve as a decorative means for the base. Such articles, particularly when colored, will usually show the effect of age through a fading of or change in, their colors if exposed in air or any other 30 oxidizing medium, or even in a vacuum. Furthermore, exposure may cause a drooping or change of shape of such articles. It is therefore desirable to surround the articles 21 with some medium which will serve 35 to prevent oxidizing or other changes in the articles whereby to maintain the same in a fresh appearing condition; and I preferably utilize a liquid for the purpose. Water is, of course, out of the question, as are other 40 liquids having the least amount of chemical activity. Experiment has shown, however, that coal oil and allied mineral oils, possess the requisite qualities of clearness and chemical inertness, and I accordingly prefer to fill the base cavity with a liquid 22 such as coal oil or the like.

Specifically, the articles 21 might be, as shown, artificial flowers and herbage made of a self-sustaining organic material, either 50 porous or impervious, and more or less transparent. As shown, the flowers and herbage are arranged as a loose bouquet, being mounted in a non-floating block 23 disposed at the bottom of the base cavity. The flowers and herbage are appropriately colored, and their 55 immersion in the coal oil 22 is found to preserve their colors with full brightness thereof. Though artificial flowers and herbage are shown, the articles 21 are, of course, not limited to the same, as the device is applicable to the provision of an unchanging display of many other decorative articles which are 60 oxidizable and are not effected by coal oil, or whatever other preservative liquid may be used. In this manner, decorative articles

placed in the base cavity for decorating the base are arranged to preserve their color and appearance of freshness indefinitely. The removability of the cap 8, it is noted, permits a change in the display if, and when, 70 such is desired, it being noted that primary functions of the cap are to protect the liquid 22 from dust and loss by evaporation. The liquid may, of course, be clear, or tinted, as 75 may be desired, the same being true of the glass top 13 and the material of the side walls of the base. In view of the foregoing, the present lamp is seen to provide an effective method for simultaneously displaying 80 and preserving certain types of perishable keep-sakes as well as purely decorative articles.

Through the use of the glass top 13, a beam of light from the globe 4 is arranged to directly illuminate the articles 21 from above 85 whereby these articles show up more clearly and transparency and other physical features of the articles are brought out in a far more effective manner than would be the case if the light entering through the sides of the base 90 from beneath the shade and elsewhere were entirely depended on to illuminate the articles. If desired, the cover glass 13 may be in the form of a light concentrating or dispersing lens for controlling the light distribution to the base cavity. In the present instance, the cap glass 13 is shown as a convex 95 lens for directing the light in a contracting conical beam downwardly through the decorative articles in the base. On the other hand, if a suffused illumination is desired, the lens would be dispersive of light passing therethrough from the globe 4.

From the foregoing description taken in connection with the accompanying drawings, the advantages of the construction and method of operation will be readily understood by those skilled in the art to which the invention appertains, and while I have described the principle of operation, together 100 with the device which I now consider to be the best embodiment thereof, I desire to have it understood that the device shown is merely 105 illustrative, and that such changes may be made, when desired, as fall within the scope 110 of the appended claims.

Having thus described my invention, I claim as new and desire to secure by Letters Patent of the United States the following:

1. In a lamp for general illumination purposes, a light source, a member providing a cylindrical receptacle having transparent walls, a cap hermetically sealing an end of said receptacle and having a transparent central portion, and means on said cap supporting 120 said light source for directing light downwardly therefrom and axially through said transparent cap portion and receptacle to illuminate articles in said receptacle inde- 125

pendently of the general illumination afforded by said light.

2. In a lamp, an electric light globe, a member providing a receptacle having transparent walls, a closure cap mounted on said receptacle and having a transparent central portion comprising a lens, means supporting said light globe on said cap in fixed relation thereto for the directing of light radially therefrom against said lens, and a light-diffusing shade fixedly mounted on said cap and generally enclosing said globe.

In testimony whereof, I affix my signature.
MOTOGO JYUMI.
